UNITED STATES PATENT OFFICE.

FRED SEIFERT, OF BOELUS, NEBRASKA.

CHIMNEY-FLUE LINER.

1,415,199.

Specification of Letters Patent.

Patented May 9, 1922.

Application filed April 11, 1921. Serial No. 460,409.

To all whom it may concern:

Be it known that I, FRED SEIFERT, a citizen of the United States, residing at Boelus, in the county of Howard and State of Nebraska, have invented certain new and useful Improvements in Chimney-Flue Liners, of which the following is a specification.

The present invention relates to attachments for chimneys, and more particularly to a liner adapted to be placed in the chimney to prevent egress of flame and sparks through crevices or cracks which may develop in the chimney construction in its side walls.

An object of the present invention is to provide a liner of this type which, among other features, possesses the advantage of being collapsible and foldable into small and compact form so that it may be easily and economically shipped in large quantities.

Another object of the invention is to provide a sectional chimney liner of this character which embodies supporting means on each of its sections for interlocking engagement with a chimney, and which has on each section a depending flange adapted to project below the interlocking means for sealing up cracks which may result about the bottom of the liner and below any support which may be provided about the chimney.

The invention also embodies the provision of a collapsible liner which may be stamped and cut from sheet metal, and which may be quickly and easily set up when ready for installation, and constitutes a permanent and secure device adapted to protect the chimney and to protect any inflammable material which may be erected about, and in proximity to the chimney.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a vertical section taken through a chimney mounted in the peak of a roof and showing a liner constructed according to the present invention mounted in the chimney;

Fig. 2 is a detail perspective view of one section of the liner;

Fig. 3 is a side elevation of an adjacent section of the liner;

Fig. 4 is a perspective view of the liner in position after the sections have been assembled and ready to be bent into shape for use;

Fig. 5 is a perspective view showing fragmentarily the upturned lower end of the liner; and

Fig. 6 is an edge view of the liner knocked down and with the sections nested together for shipment.

Referring to the drawing, 25 designates a chimney of any approved type which, in the usual manner, is provided with a layer of cement or plaster 26, forming the usual lining employed. The chimney 25 is shown as passing through the peak of a roof 27, and the roof carries a frame 28 which surrounds and embraces the chimney 25 at a suitable distance below the top of the chimney.

Frequently, settling of the chimney causes the lower part thereof to sag or drop down, while the upper part of the chimney, embraced in the frame 28, is held in proper position with the result that cracks or crevices 29 are formed immediately below the frame 28. The frame 28 is, in nearly all instances, constructed of wood as is also the rafters and other parts of the roof 27. When the crack 29 occurs in the wall of the chimney, the cement or plaster 26 cracks and breaks with the brick work, with the result that flame and sparks passing up the chimney are free to pass out through the crack 29, and come into contact with the wooden frame 28 and roof 27.

It is found that a great many fires occur incident to this fault in the construction and settling of the chimney 25, and the present invention is designed to provide a simply constructed and handled device, which may be quickly erected in the course of chimney construction and used for preventing the passing of sparks and fire out through the walls of the chimney beneath the roof.

The liner is shown substantially rectangular in shape, for the purpose of description, and it comprises end sections 30 and 31 and side sections 32. The sections are formed from sheet metal suitably cut and bent into the desired form, and which are of the desired length to extend, when erected in the chimney, sufficiently far above and below the peak of the roof to prevent injury.

thereto incident to the settling or cracking of the chimney walls.

The section 30, as shown in Fig. 2, comprises a flat body plate having lateral flanges 33 which are bent at right angles in the same direction from the body plate, to provide attaching means therefor. The upper end of the body plate 30 is provided with a flange portion 34 adapted to be turned outwardly 10 at right angles to the body plate from the position shown in Fig. 4 to the position shown in Fig. 2, for providing a top anchor to the section. The section 30 is also provided, intermediate its ends, but toward 15 the lower end thereof, with a stamped and outwardly pressed flange 35 forming a lower anchor for the section.

The flanges 34 and 35 extend in the same direction outwardly from the section 30, 20 and are adapted to be embedded in the mortar or other plastic material in the chimney wall construction, for firmly holding the liner section 30 from displacement. It will be noted that the section 30 projects considerably below the lower flange 35 so as 25 to project down into the chimney to a point considerably below the lower anchor.

The other end section 31 is of similar construction with the exception of its trans- 30 verse dimensions, the same being fore- shortened at opposite ends a distance equal to the thickness of the inturned flanges 33 of the other section 30. The result of such construction is seen in Fig. 6 wherein the 35 end section 30 telescopes or fits over the end section 31 to form therewith a substantially narrow compartment in which are nested the side sections 32.

The sides 32 are in the form of sheet metal 40 body plates having at their upper ends the outturned anchoring flanges 34 and provided intermediate their ends with the outturned lower anchoring flanges 35. This arrangement of flanges 34 and 35 prevails through- 45 out the sections so that when the sections are assembled in the position shown in Fig. 4, the upper flanges 34 register in a top horizontal plane, while the lower flanges 35 register in a lower horizontal plane which 50 passes through the liner at a point spaced considerably above the lower end of the liner.

The flanges 33 of the end sections 30 and 55 31 are adapted to lap over against the inner faces of the sides 32, and side flanges 33 and the lateral portions of the sides 32 are apertured to the desired extent for receiving rivets 36 or the like used in assembling the sections together when setting the liner 60 up in position for use.

It is apparent that the ends 30 and 31, when manufactured, may be nested or collapsed against the sides 32 so as to provide a package which is relatively flat and 65 which occupies but small space, the flanges

33 being preferably proportioned with respect to the thicknesses of the sides 32 for relieving the flanges 33 from any strain imposed by lateral thrust against the ends 30 and 31 when the parts are nested together. 70 Thus, when the device is collapsed or folded, it is capable of withstanding considerable hard usage and pressure, and the devices may be stacked upon each other in large quantities without injury to the same. 75

The provision of the overlapping flanges 33 in the knocked down device protects the edges of the sides 32 and also prevents the same from sliding one upon the other from between the ends. When set up, the sides 32 80 are placed against the outer faces of the flanges 33 and the rivets 36 are then driven into place. The device as shipped, has its sections in flat condition such as shown in Fig. 4, wherein the flanges 34 and 35 are 85 unbent and lie in the general planes of their respective sections. When the device is received at its destination for use, the ends and sides are first secured together by the rivets 36, into the form shown in Fig. 4, 90 when the flanges 34 and 35 may then be bent outwardly and downwardly to provide the spaced apart anchors, as shown in Fig. 1.

In installing the device in the chimney, 95 the anchors 34 and 35 are embedded in the mortar or other plastic substances used in securing the bricks together, with one anchor 34 above the horizontal plane of the peak of the roof, and the lower anchor 35 below 100 the lower end of the frame 28. When the liner is thus mounted in the chimney, its lower end or skirt projects below the frame 28 to a considerable distance so that when the chimney 25 settles, its lower portion will 105 remain sealed with respect to its upper portion by reason of the lower end or skirt of the liner.

I do not wish to be restricted to the size, 110 form, and proportions of the various parts, and obviously changes could be made in the construction herein described without departing from the spirit of the invention, it being only necessary that such changes fall within the scope of the appended claims. 115

What is claimed is:

1. In a sectional nesting chimney liner, a pair of ends and a pair of sides adapted to be fastened to said ends, each of said ends being provided with a pair of inturned lateral flanges and the flanges of one end being arranged to interfit with the flanges of the other end to provide between the ends a relatively flat compartment, said sides being adapted to fit in said compartment between the ends and the edges of said sides being overlapped by the flanges in the collapsed position whereby the edges of the sides are protected and kept between the ends. 120
2. In a sectional nesting chimney liner, 125

a pair of ends and a pair of sides adapted to be connected to said ends, each of said ends having a pair of inturned lateral flanges and the flanges of one end being arranged to interfit with the flanges of the other end to provide between the ends a relatively flat compartment, and said sides being adapted to fit in said compartment between the ends for nesting said chimney liner together.

In testimony whereof, I have affixed my signature in presence of two witnesses.

FRED SEIFERT.
